[57] ABSTRACT

In a preferred embodiment, a series of parallel vertical steam-conducting pipes are covered on one side thereof with a metal contoured sheet of an area sufficient to be contoured to the profile of the pipes to an extent making possible the snapping-on of the sheet onto the pipes, together with top and bottom covers respectively to cover the tops and bottoms of the pipes to thereby substantially conceal them from view, and the metal sheet being connected to the respective pipes by heat-conducting metallic connectors.

FIG. 1.

FIG. 2.

FIG. 3.

RADIATOR FOR CENTRAL HEATING

This invention relates to an improved radiator design for improved heat transfer to and from room-warming outer radiating surfaces of the radiator.

BACKGROUND TO THE INVENTION

Prior to the present invention, there has been considerable and significant heating inefficiency of radiator-heated spaces such as rooms of a home or business establishment, due to the poor or minimal radiation of heat from the radiator steam or vapor carrying pipes.

SUMMARY OF THE INVENTION

It is an object of the present invention to overcome the difficulties and short-comings of prior radiators of the above-noted types.

Another object is to obtain a greater surface for the radiating of heat therefrom.

Another object is to obtain the preceding one-or-more objects while concurrently achieving an aesthetically pleasing appearance.

Another object is to obtain a radiator of simple and inexpensive nature and manufacture, while obtaining one or more of the preceding objects.

Other objects become apparent from the preceding and following disclosure.

Broadly the invention relates in a preferred embodiment to the improving of heat exchange between metal radiating sheet and the heating-fluid conducting pipes, and the simplification of the radiator structure, and broadly the objects of the invention are obtained by a metal sheet which has been profiled in such an undercut way that it may be snap-fastened onto the pipes by snap-on action of heat-conducting surfaces. In this manner, the metal sheet may be clamped around the pipes over their entire straight part, whereby a very intensive heat exchange is reached. The pipes may be arranged horizontally or vertically, preferably vertically. After snapping the metal sheet around the pipes, in order to hide the pipe bends at the upper and lower side, a cover for the top plane and another cover for the bottom plane may each be installed. When the profiling fits around the pipes ideal heat exchange is reached. The invention relates to a radiator for a central heating system and having a number of preferably straight pipes or pipe parts, arranged at intervals and through which the heating medium is passable with the sheet profiled along its broad face to fit the contour of the pipes or pipe parts such that the opposite broad face of the sheet faces a direction toward the room space to be heated, with the sheet connected in a heat-conductive manner to the pipe system.

When the pipes are of circular cross-section of cylindrical nature, the profiling of the sheet preferably comprises a circular recess for each pipe to accomodate the pipe to the profiling of the sheet for each pipe at a contour angle greater than 180° to thereby enable a snap-on arrangement, the inner diameter of the recess being equal or slightly larger than the diameter of the pipe.

The pipes are preferably arranged with the straight parts parallel and vertical, the joining parts between the pipes being concealed by covers at the top and bottom. The straight parts may optionally be horizontal.

The profiling of the sheet around the pipe parts ensures good heat exchange and simple construction and assembly.

A radiator in accordance with this invention is shown by way of example in the accompanying drawings wherein:

FIG. 1 illustrates a typical front-side perspective view of a series of pipes serially connected in flow series.

FIG. 2 illustrates a typical front-side perspective view of the invention's profile-contoured sheet contoured to fit in a snap-on fashion onto the pipes of FIG. 1.

FIG. 3 illustrates a typical front-side perspective view of the combination-radiator device of this invention in the assembled state.

DETAILED DESCRIPTION OF THE INVENTION

The pipe arrangements shown in the FIGS. 1-3 have straight vertical pipe parts 1 joined by horizontal portions 2. Water inlet and outlet couplings 3 are provided at one side of the arrangement. The profiled heat radiating sheet 4 shown in FIG. 2 has part-circular recesses 5 arranged to snap-over each pipe part 1 and surround the pipes over an arc greater than 180°, the springy nature of the metal sheet allowing this snap-over action and ensuring good heat connection between the sheets and the pipes.

An assembled radiator is shown in FIG. 3 and box-like enclosure 6 cover the pipe part 2 and the sides of the radiator are enclosed by bent-over end portions 7 of the sheet 4.

It is to be understood that it is within the scope and spirit of the present invention to make such modifications and substitution of equivalents as would be apparent to a person of ordinary skill.

I claim:

1. A radiator unit comprising in combination: a continuous pipe element preshaped into a plurality of serially interconnected substantially parallel sections spaced apart predetermined distances from one another consecutively spaced one after the other and interconnected with preceding and following ones of the serially interconnected substantially parallel sections by respective interconnecting pipe portions of the pipe element such that flow space through the pipe element is serially continuous throughout the sections and interconnecting portions, said interconnecting portions being located at each of opposite ends of adjacent interconnected sections; a resilient metal sheet extending in a plane substantially parallel to the longitudinal axes of said sections, and having the sheet profile-contoured to substantially circumscribe in series each of said sections such that said sheet is mounted on said sections by snap-on intimate connections between opposite end ones of said interconnecting pipe portions; and first and second end-cover elements, the first end-cover section being shaped to fasten enclosingly over the interconnecting pipe portions located at one end of the plurality of sections and the second end-cover section being shaped to fasten enclosingly over the interconnecting pipe portions located at an opposite other end of the plurality of sections; said pipe element being substantially circular in cross-section through said sections and pipe portions, and said sections each being substantially straight along its longitudinal axis.
